BARBECUE AND FIREPLACE TONGS

Donald J. Capps, 5216 Willmonte Ave.,
Temple City, Calif. 91780

Filed Apr. 22, 1968, Ser. No. 11,572

Term of patent 14 years

U.S. Cl. D23—100
Int. Cl. D23—03

FIG. 1 is a fragmentary side elevational view of the barbecue and fireplace tongs showing my new design, the opposite side being the same in appearance;

FIG. 2 is a perspective view of the tongs, the opposite side being the same in appearance;

FIG. 3 is a sectional view taken on line 3—3 of FIG. 2.

I claim:

The ornamental design for barbecue and fireplace tongs, substantially as shown and described.
